VACUUM HANDLING DEVICE

Harry H. Lenhart, Cleveland, Ohio

Application September 10, 1948, Serial No. 48,689

9 Claims. (Cl. 294—64)

1

This invention relates to a handling implement primarily adapted for lifting flat sheet material such as sheet steel, glass and the like but which is also useful in handling any object having a flat, smooth surface.

An object of the invention is to provide an object-handling implement operating on the well-known suction-cup principle which is quickly and easily connected to the object and which is just as quickly and easily detached therefrom.

Another object of the invention is to provide a suction-type handling implement for lifting and carrying objects which automatically exerts a greater suction for heavier objects.

A further object of the invention is to provide a suction-cup lifting implement which is inexpensive in its cost yet rugged in its construction and which will exert a suctional force substantially proportional to the weight of the object to be lifted.

For a better understanding of the present invention, together with other and further objects thereof, reference is had to the following description taken in connection with the accompanying drawings, and its scope will be pointed out in the appended claims.

In accordance with the invention there is provided a handling implement primarily for flat sheets of rigid material which comprises a resilient diaphragm whose peripheral edge lies in a plane. A rigid cup is mounted over the diaphragm with the lip of the cup engaging the peripheral edge portion of the diaphragm and with the central portion of the cup spaced away from the central portion of the diaphragm. One end of a stem which extends through a hole in the cup is connected to the central portion of the diaphragm and the other end of the stem is connected to a first handle which is adapted to be gripped by the fingers of an operator. A second handle is provided and means connect it to the cup. The first handle is positioned between the cup and the second handle and is spaced away from the second handle whereby an operator with one hand around the two handles, upon squeezing, can pull the first handle toward the second handle thereby pulling the central portion of the diaphragm up into the cup.

Fig. 1 of the single sheet of drawing shows a side view of the invention in position on an object to be lifted.

Fig. 2 is a side view of the device ready to lift the object; and

Fig. 3 is a cross-sectional view taken along line 3—3 of Fig. 2.

The handling implement of this invention is primarily adapted for lifting flat sheets of metal

2

or glass such as the sheet identified by the reference character 10 in the drawing, although it may of course be used for lifting many other objects.

5 A resilient diaphragm 11, preferably made of good grade rubber, is provided. It may be slightly concave in its unstressed condition and its peripheral edge lies in a plane so that when it is placed firmly on the sheet 10 it contacts the sheet around its entire periphery. A rigid metal cup 12 is mounted over the rubber diaphragm 11 with the central portion of the diaphragm within the cup, and the peripheral lip of the cup engages the peripheral edge portion of the rubber diaphragm 11. The cup 12 is sufficiently deep that the central portion of the slightly concave diaphragm 11 is normally spaced away from the bottom thereof.

One end of a stem 13 is integral with or connected to a plate 14 molded into the central portion of the rubber diaphragm 11 thereby securing the stem 13 to the diaphragm 11. The stem 13 is connected to a first handle 17 which is adapted to be gripped by the fingers of an operator.

20 A second handle 15 is provided and means such as the metal compression member 16 connect the handle 15 to the metal cup 12. A washer 18, preferably though not necessarily, is positioned between the bottom of the cup and the central portion 16' of the compression member 16. One end of a flat spring 20 is connected to the underneath side of the handle 15 within a hollowed-out location 15'. The other end 21 of the spring 20 rests up against the handle 15 and the central portion 22 is bowed away therefrom down toward the upper surface of the handle 17. A slot 23 is provided in the spring 20 and a large headed stud 24 extends through the slot into the top of the handle 17. This secures the handle 17 to the handle 15 but permits limited relative movement between the two handles.

When an operator wishes to lift an object he places the lifting device on it with the rubber cup in engagement with the object. The operator then presses the palm of his hand down on the handle 15 with the diaphragm 11 resting on a sheet and compressional forces are transmitted through the compression member 16 and the washer 18 to the metal cup 12 and thence to the peripheral edge portion of the diaphragm to seal it against the sheet 10 which is to be lifted. The operator's fingers curve underneath the handle 17 in a position such that he can pull the handle 17 up into the hollow 20 in the interior of the handle 15. This pulls the central portion of the rubber diaphragm 11 up into the interior of the

metal cup 12 and establishes a partial vacuum between the diaphragm and the plate 10, and simultaneously flattens the spring 20. The operator can then lift the plate 10 as the lifting device is securely attached to it. So long as the operator maintains the handle 17 in its retracted position the plate 10 will be securely held, but upon the operator releasing his finger pressure on the handle 17 the partial vacuum together with the spring 20 returning to its natural position will pull the handle 17 back into its original position and the partial vacuum will be reduced permitting the handling implement to be easily disengaged from the plate. It will be seen, therefore, that only so long as the operator maintains his finger pressure the plate will be connected to the handling implement, and that the release of the plate is automatic upon the plate being set down and the operator releasing the handle 17. Thus the device lends itself to very rapid lifting, carrying and releasing of sheet material. Such construction also automatically establishes a greater partial vacuum and therefore a more positive action for heavier sheet material than for lighter material. This is because practically all of the weight of the material 10 is transmitted through handle 17 to the operator's fingers and results in increased forces tending to hold the handle 17 up into the handle 15. This means that the operator need not squeeze the two handles together while transporting the load and affords a comfortable carrying position for heavy loads.

While there have been described what are at present considered to be the preferred embodiments of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A handling implement primarily for flat sheets of rigid material comprising, a solid resilient diaphragm whose peripheral edge lies in a plane, a rigid cup mounted over said diaphragm with the lip of said cup engaging the peripheral edge portion of said diaphragm and with the central portion of the cup spaced away from the central portion of said diaphragm, a stem having one end connected to the central portion of the diaphragm extending up through a hole in the central portion of said cup, a first handle connected to and symmetrically above the other end of said stem and adapted to be gripped by the fingers of an operator, a second handle symmetrically above said stem and above and spaced from said first handle, means connecting said second handle directly to said first handle, and substantially rigid force transfer means in engagement with said second handle and said rigid cup for transferring compressional forces from said second handle to said rigid cup whereby an operator with one hand around the two handles upon squeezing the two handles together can pull the first handle toward the second handle thereby pulling the central portion of said diaphragm up into said cup while simultaneously pushing the handling implement down against a flat sheet.

2. A handling implement as set forth in claim 1, further characterized by said means connecting said second handle to said cup being substantially rigid to compressional forces exerted in a direction from said second handle toward said cup whereby an operator can press said dia-

phragm firmly against the object to be handled.

3. A handling implement as set forth in claim 1, further characterized by said second handle being hollow at its underneath side and by said first handle being adapted to fit into the hollow within said second handle.

4. A handling implement as set forth in claim 1, further characterized by spring means located between said first and said second handles biasing said handles away from each other.

5. A handling implement as set forth in claim 4, further characterized by means connecting said spring means to each of said handles.

6. A handling implement primarily for flat

15 sheets of rigid material comprising, a solid resilient diaphragm whose peripheral edge lies in a plane, a rigid cup mounted over said diaphragm with the lip of said cup engaging the peripheral edge portion of said diaphragm and with the central portion of the cup spaced away from the central portion of said diaphragm, a stem having one end connected to the central portion of the

20 diaphragm extending up through a hole in the central portion of said cup, a first handle connected to and symmetrically above the other end of said stem and adapted to be gripped by the fingers of an operator, a second handle, connection means connecting said second handle permanently to said cup with the handle per-

25 manently located symmetrically above said stem, said connection means being substantially rigid to compressional forces exerted in a direction from said second handle toward said cup whereby an operator using said second handle can press said

30 diaphragm firmly against the object to be han-

dled, said first handle being positioned between said cup and said second handle and being spaced away from said second handle whereby an operator with one hand around the two handles upon

40 squeezing the two handles together can pull the first handle toward the second handle thereby pulling the central portion of said diaphragm up into said cup while simultaneously pushing the handling implement down against a flat sheet.

7. A handling implement as set forth in claim

45 6, further characterized by said second handle being hollow at its underneath side and by said first handle being positioned within said hollow but spaced from said second handle.

8. A handling implement as set forth in claim

50 7, further characterized by spring means mounted between said first and said second handles biasing said handles away from each other.

9. A handling implement as set forth in claim

55 8, further characterized by means connecting said spring means to each of said handles.
